SHOVEL

Filed March 13, 1930

INVENTOR.

Ole A. Lysne

BY

David E. Carlson

ATTORNEY.

UNITED STATES PATENT OFFICE

OLE A. LYSNE, OF NORTHFIELD, MINNESOTA

SHOVEL

Application filed March 13, 1930. Serial No. 435,575.

My invention relates to shovels and the main object is to provide a shovel with new and novel features including replaceable blade means of highly efficient, inexpensive 5 and useful, construction as hereinafter fully set forth, reference being had to the accompanying drawing, in which,—

Fig. 1 is a top or plan view of my improved shovel and a portion of its handle.

10 Fig. 2 is an enlarged longitudinal sectional elevation of the shovel as on line 2—2 in Fig. 1.

Fig. 3 is a top view of the lower shovel blade retaining plate of my device.

15 Fig. 4 is a top view of my replaceable shovel blade only.

Fig. 5 is an enlarged sectional view transversely of the blade device, as on line 5—5 in Fig. 3.

20 Fig. 6 is a perspective fragmentary view, showing the left end of the lower blade retaining plate shown in Fig. 3.

Referring to the drawing by reference numerals, 10 designates a metal shovel body or ladle of approximately desired form and to the rear part of which is removably fixed as by means of a U-bolt 11 and a clip 12 or equivalent means, a handle 13. The front edge part of the ladle is of course a transverse plane relative to the handle 13 and the construction thereof embodies a replaceable blade as will presently be described. It is well known that this front edge of any shovel is the first part of the ladle to be 30 worn out or is worn uneven, curls up or is otherwise deformed by wear and tear.

10A is the base of the shovel ladle, usually flat and having a transverse forward edge 10B. The upper edge or rim of the ladle proper is preferably formed beaded as 10C and inclosing a heavy wire 14 (see Figs. 1 and 2), said wire being preferably tapered toward its two forward ends which project beyond the said edge 10B for a purpose 45 which will now be set forth.

The front edge part of my improved shovel comprises an approximately quadrangular elongated blade 15 removably retained between a pair of plates 16 and 17 of which 16 is an upper plate and 17 a lower

plate. The blade 15 projects forward from the aligned front edges of plates 16—17, as shown, when in operative position. Plate 16 is offset longitudinally and downward, making its rear part a lowered ledge on 55 which the front edge part 10B of the ladle bottom 10A is placed against the offset part and thus 10A and the upper part of plate 16 are on a common plane both ways from the offset 16A (see Fig. 5). The lower plate 17 60 is fixed to the rear and lower offset part of plate 16 by means of a series of rivets 18, some or all of which rivets may be passed through ladle bottom 10A to secure said three parts together firmly. Obviously the 65 plates 16—17 are in parallel spaced and fixed relation to each other forward of the offset, forming a receiving pocket in which the blade 15 is retained. The means for retaining the blade comprises two or more 70 fixed studs 19 projecting upwardly from the lower plate 16. Said plate is also provided at each end with upwardly projecting fixed blocks, 20R and 20L, each with corresponding angular face 20R' and 20L', said blocks 75 being of a thickness corresponding to thickness of blade 15.

Said blade is provided at its left end with a notch 15N having a sloping side 15N' adapted to be engaged against the sloping face 20L' of block 20L and at the right hand end blade 15 is cut off angularly as at 15A to provide a face to bear against the angular face of block 20R (see dotted position of blade 15 in Fig. 3) when the blade is in 80 operative position. The inner edge part of the blade is further provided with two or more angular slits 21, one for each stud 19, so that the blade can be inserted between the plates with the slits 21 guiding it inwardly and angularly to the innermost position, shown dotted in Fig. 3. Then the top plate 16 is pressed down on top of the blade, said plate being provided with apertures to engage over the parts of studs 19 projecting 85 above the blade and said latter parts hammered down to hold the blade and plates together firmly. The lower plate 17 is provided with extensions or ears 17E at its 90 opposite ends and it will be readily under-

stood that these ears are bent inwardly, after placement of blade 15, and thence beaded around the protruding front ends of the wire 14, as from dotted to full line positions of said ears distinctly shown in Fig. 1 (see also Fig. 3).

The studs 19 need not necessarily be riveted but to further hold the blade 15 in place I provide vertically registering apertures 21 10 in the plates 16—17 and a like aperture 22 in the blade 15, all three to be aligned when the blade is in position and through which a holding rivet 23 is placed and clinched (see Figs. 1 and 5).

15 In this latter form it will be readily understood that a worn blade 15 is easily replaced by simply chipping off the end of rivet 23, removing it and taking out the old blade, then replacing it with a new one as 20 described. The advantages of this construction are so obvious as to need no further description thereof. A feature of this invention desired to be stressed is the wire reinforcing bead 14 tapered toward both ends. I 25 have illustrated and described my invention in a preferred embodiment thereof, variations of details and application being possible without departing from the scope and spirit of the invention.

30 I claim:

1. A shovel ladle comprising a metal blade with plane transverse front edge, the body of said ladle formed with rearwardly rising edge portions, said edge portions comprising 35 a continuous bead, a single wire within said bead and tapered toward its ends, and a front blade device removably fixed to said transverse front edge of the ladle and comprising a double plate, the upper part of 40 said plate offset to provide a forwardly directed opening between the two parts of said plate, a front shovel blade adapted to be slidably inserted in said opening and guide plates fixed to said lower plate to guide and 45 retain said blade in said opening and further means fixed in said lower plate to guide the blade to operative position and said blade normally projecting forward of the front edge of said plate member.

50 2. The structure specified in claim 1 in which said offset part of the plate is downwardly at the rear edge part thereof and said offset rear part adapted to bear against the lower front edge part of the shovel proper 55 and means for securing said parts together.

3. A shovel ladle comprising a metal blade with plane transverse front edge, the body of said ladle formed with rearwardly rising 60 edge portions, said edge portions comprising a continuous bead, a single wire within said bead and tapered toward its ends, and a front blade device removably fixed to said transverse front edge of the ladle and comprising a double plate, the upper part of 65

said plate offset to provide a forwardly directed opening between the two parts of said plate, a front shovel blade adapted to be slidably inserted in said opening and guide plates fixed to said lower plate to guide and 70 retain said blade in said opening and further means fixed in said lower plate to guide the blade to operative position and said blade normally projecting forward of the front edge of said plate member, said latter guide 75 means comprising fixed studs in the lower plate and said plate provided with angularly and rearwardly directed slits one for each said stud, the blade adapted to be slid rearwardly between the said plates with its slit 80 parts simultaneously guided by and straddling said studs, said plates and said blade provided with apertures adapted to register vertically for insertion of a rivet to hold the plates and blade in correct relative positions. 85

4. A shovel ladle comprising a metal blade with plane transverse front edge, the body of said ladle formed with rearwardly rising edge portions, said edge portions comprising a continuous reinforcing bead toward its 90 ends, said wire ends protruding forwardly from said beaded parts, a removable shovel blade arranged transversely of the ladle and forward of its front edge, means for removably retaining said blade in about a common 95 plane with the bottom of the ladle, said latter means comprising a pair of plates with their front portions apart and adapted to retain said blade therebetween, endwise integral extensions provided on the lower of 100 said two plates and said protruding parts of the beading wire normally extending over said extended parts, and said latter parts adapted to be bent inwardly over and about said wire ends for the purpose set forth. 105

In testimony whereof I affix my signature.
OLE A. LYSNE.
